UNITED STATES PATENT OFFICE.

H. STANSBURY NORSE, OF NEW YORK, N. Y.

DESIGN FOR A HAT.

SPECIFICATION forming part of Design No. 12,894, dated April 18, 1882.

Application filed February 17, 1882. Term of patent 3½ years.

To all whom it may concern:

Be it known that I, H. STANSBURY NORSE, a citizen of the United States, residing in the city, county, and State of New York, have invented and produced a new and original Design for Hats; and I do hereby declare that the following is a full, clear, and exact description thereof, reference being had to the accompanying drawings, and to the letters of reference marked thereon, making a part of this specification.

Figure 1 is a side elevation, and Fig. 2 a top view, of my newly-designed hat.

The leading feature of my design consists in a nodulous crown and an indented brim, the whole presenting in combination the general form of a sunflower, the crown of the hat serving to represent the pistils, and the brim the petals, of the flower.

A is the crown, and B the brim, of the hat, and C a ribbon encircling the crown.

The crown B is fashioned to present a nodulous surface substantially as shown in the drawings, and may be colored to approximate

more or less closely the brown shade of the center of a full-blown sunflower.

The brim A is likewise formed with a pointed or serrated edge, and its surface is broken or fashioned in any suitable manner to present substantially the appearance of radial layers, and may be colored a yellow shade to resemble the petals of the sunflower.

The ribbon C, which may be of a brown shade, encircles the crown in the customary manner.

I claim—

The design for a hat herein shown and described, the same consisting of the nodulous crown A and the brim B, having a serrated edge and broken surface, the whole resembling in general appearance an enlarged sunflower.

In testimony whereof I have signed my name to this specification in the presence of two subscribing witnesses.

H. STANSBURY NORSE.

Witnesses:

DAVID A. BURR,
P. ELBERT NOSTRAND.
